UNITED STATES PATENT OFFICE.

ROBERT H. WARREN, OF NEWARK, NEW JERSEY.

DESIGN FOR A STAIR-CARPET BUTTON.

SPECIFICATION forming part of Design No. 24,632, dated August 27, 1895.

Application filed August 1, 1895. Serial No. 557,904. Term of patent 7 years.

To all whom it may concern:

Be it known that I, ROBERT H. WARREN, a citizen of the United States, residing at Newark, in the county of Essex and State of New Jersey, have invented and produced a new and original Design for Stair-Carpet Buttons; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 In the drawings, Figure 1 is an elevation, and Fig. 2 a sectional view, of my newly-designed stair-carpet button, taken on line *x*, these views being deemed necessary and sufficient to fully illustrate my design.

20 The leading feature of my design consists in the stair-carpet button, square or four-sided in outline and having a raised center, which is perforated, and around the perforation is displayed ornaments, the axes of which are in 25 lines radiating from said center.

In the drawings, *a* indicates the button, which is four-sided. The center of said button is raised, as indicated in Fig. 2, and is perforated, as at *b*, and around this perforation I display a ring-shaped ornament *c*, from which are radiating stems having berry-shaped ornamental members *e* at their outer extremities. Between said berry-shaped ornaments are formed or displayed conventional flower-shaped ornaments *f*, having petal-shaped center members *f'*, which are more or less pointed and lie in the angles of the button.

What I claim is—

The design for a stair carpet button herein shown and described.

In testimony that I claim the foregoing I have hereunto set my hand this 25th day of July, 1895.

ROBERT H. WARREN.
